United States Patent Office

Des. 228,047

Patented Aug. 7, 1973

228,047

JERSEY

Andrew J. N. Alexander, Port Credit, Ontario, Canada,
assignor to Maple Leaf Gardens Limited, Toronto,
Ontario, Canada

Filed Apr. 8, 1971, Ser. No. 132,629

Term of patent 14 years

Int. Cl. D2—02

U.S. Cl. D2—46

FIG. 1

FIG. 2

FIG. 3

FIG. 1 is a front elevational view of a jersey showing my new design;

FIG. 2 is a side elevational view thereof; and FIG. 3 is a rear elevational view.

I claim:

The ornamental design for a jersey, substantially as shown.
